CLAIM

The ornamental design for a camera utility bag, as shown and described.

DESCRIPTION

FIG. 1 is a perspective view of a camera utility bag showing my new design;

FIG. 2 is a front elevational view;

FIG. 3 is a rear elevational view;

FIG. 4 is a right side elevational view;

FIG. 5 is a left side elevational view;

FIG. 6 is a top plan view;

FIG. 7 is a bottom plan view; and

FIG. 8 is a perspective view with the top and front compartments of the bag opened.

The partial showing of surface shading indicating a fabric texture is understood to be continuous on those surfaces where shown.

FIG.1

FIG.2

FIG. 3

FIG. 4

FIG. 5

FIG. 8

FIG. 6

FIG. 7
